POCKET TOOL

Alwin J. Stahel, New Brighton, Minn., assignor to Arthur Salm Inc., Chicago, Ill.

Filed June 29, 1970, Ser. No. 23,752

Term of patent 14 years

Int. Cl. D8—05

U.S. Cl. D8—99

FIG. 1.

FIG. 2.

FIG. 3.

FIG. 4.

FIG. 5.

FIG. 6.

FIG. 1 is a rear elevation view of a pocket tool incorporating my new design;

FIG. 2 is a front elevation view of the pocket tool of FIG. 1;

FIG. 3 is a left side elevation view of the pocket tool of FIG. 1;

FIG. 4 is a right side elevation view of the pocket tool of FIG. 1;

FIG. 5 is an enlarged top end view of the pocket tool of FIG. 1; and

FIG. 6 is an enlarged bottom end view of the pocket tool of FIG. 1.

I claim:

The ornamental design for a pocket tool, substantially as shown.
